UNITED STATES PATENT OFFICE.

ANDREAS GULBRANDSEN HOVDE, OF HÖNEFOS, NORWAY.

CLOCK STRIKING MECHANISM.

SPECIFICATION forming part of Letters Patent No. 330,896, dated November 24, 1885.

Application filed August 11, 1885. Serial No. 174,149. (No model.)

To all whom it may concern:

Be it known that I, ANDREAS GULBRANDSEN HOVDE, a subject of the King of Norway, and residing in the town of Hönefoss, Norway, have 5 invented certain new and useful Improvements in Striking-Trains for Clocks; and I do hereby declare the following to be a full, clear, and exact description of the invention, such as will enable others skilled in the art to which 10 it appertains to make and use the same.

My invention relates to an improvement in striking-trains for clocks.

The object is to provide striking mechanism of simple construction in which the rolling friction shall be materially lessened.

With this end in view my invention consists in certain features of construction and combinations of parts, as will be hereinafter described, and pointed out in the claims.

20 In the accompanying drawings, Figure 1 is a view of a portion of clock-work embodying my invention. Fig. 2 is a detached view showing the position of the escapement just before the clock is ready to strike, and Fig. 3 is a 25 similar view showing one of its positions while striking.

The striking-train represented in the drawings consists of a movement mechanism and a regulating mechanism. The movement mechanism 30 comprises the pinion or escapement-disk s , provided with the tooth s' and recess s'' , the disengaging-arm a' , and the hammer b , balanced by a counter-weight, b' , all these parts being rigidly secured on the hammer-axle a . The 35 hammer is continuously drawn toward the bell by means of a spring, x , by a weight acting independently, or by the weight of the hammer itself.

The regulating mechanism consists of the 40 step-wheel m , secured on the sleeve of the hour-hand, or otherwise adapted to make one revolution every twelve hours, the two-armed lever ff' adapted to stop the striking-motion at the proper time, and the toothed escapement-wheel r , having a series of studs or stops, I, II, &c., on its face; or a separate disk might be employed to carry the stops and adapted to rotate simultaneously with the escapement-wheel r . The escapement-wheel r 45 is constantly under tension tending to force it to the left by the employment of a spring or weight, y , attached to its axle.

A represents the center arbor, to which the minute-hand is attached, and which is adapted to make one revolution every hour, as is usual. 55 The step-wheel m , above referred to, is sleeved on the arbor A, an intermediate train of gear, $p p'$, meshing with the gear $q q'$, located on the arbor and hour-hand sleeve, respectively, to transmit the power of the clock - actuating 60 spring or weight, as the case may be, to the center arbor and hour-sleeve loosely mounted thereon.

k is the bell.

The free end of the disengaging-arm a' rests 65 in contact with the under face of a disk, l , secured on the center arbor, and hence making one revolution every hour. The disk l has a notch or groove, l' , formed in its face, into which the end of the arm a' falls each hour, 70 at which time the arm is free to swing away from the disk l , the hammer-axle thereby left free to rock, and the tooth s' on the escapement-disk s free to disengage the opposing tooth on the escapement-wheel r . The branch 75 f' of the lever ff' is adapted to rest on the face of the wheel m , and as it follows the successive steps formed thereon it elevates or depresses the arm f just enough to cause it to engage the proper stop on the face of the 80 wheel r .

The position represented in Fig. 1 is that which is assumed as the clock is about to strike two. As the end of the arm a' enters the groove l' , the tooth r' on the wheel r , pressing 85 against the nose or tooth s' on the disk s , rotates the hammer-axle toward the right, and as the tooth r' slips past the tooth s' the tension of the spring x on the hammer-axle forces the hammer in contact with the bell. As the 90 hammer rebounds the tooth r^2 on the wheel r engages the tooth s' , the hammer is again thrown back, and as soon as the tooth r^2 passes the tooth s' a second stroke of the hammer takes place. The end of the arm f , or a leaf 95 or tooth attached to the end, now engages the stop marked II. The wheel r is thereby held in check, and the striking ceases. As the shoulder at the back of the groove l' engages the arm a' , it presses downwardly on the arm, 100 thereby rotating the hammer-axle slightly toward the left, and, through the tooth s' in engagement with the tooth r^3 on the wheel r , rotates the wheel r slightly toward the right,

and releases the end of the arm *f* from the stop or pin II. At the same time, the wheel *m* having rotated a short distance to the right, the end of the arm *f'* has dropped onto the 5 next step, and has carried with it the end of the arm *f* to a point below the stop II, and at a proper elevation to intercept the stop III. The distance from the stop II to the stop III, measured in a direction opposite to that in 10 in which the wheel *r* revolves, corresponds to three teeth on the wheel *r*, and hence as the disk *l* presents its groove *l'* to the end of the arm *a'* at the end of the next hour the clock will strike three. In the same manner, the 15 distances from stop III to IV, from stop IV to stop V, and from stop V to stop VI correspond, respectively, to four, five, and six teeth on the wheel *r*, and the clock will therefore strike four, five, and six. At the time when 20 the clock strikes six the arm *f'* rests upon the lowest step on the wheel—viz., that step which is nearest its axle, and as the wheel continues to revolve, the arm *f'*, and hence the arm *f*, will be raised one step. The wheel *r* has thirteen 25 teeth; hence the distance from the stop VI to the stop V, measured in the same direction as before, will correspond to seven teeth, and the clock will next strike seven. The distances from V to IV, from IV to III, 30 from III to II, from II to I, and from I to XII, measured in the same direction as before, correspond, respectively, to eight, nine, ten, eleven and twelve teeth on the wheel *r*, and the clock will therefore strike, in order, eight, 35 nine, ten, eleven, and twelve.

When the escapement-wheel is provided with thirteen teeth, as above described, it will be required to make six revolutions every twelve hours, since there are seventy-eight strokes 40 required to strike the twelve hours, and one tooth corresponds to one stroke.

By increasing the number of teeth to twenty-six or thirty-nine, the number of revolutions required of the wheel *r* during the twelve 45 hours might be decreased to three or two, respectively. This change would, however, only necessitate a slight change in the arrangement of the stops on the escapement-wheel and the steps on the heart-wheel, and its operation would be quite similar to that already 50 described.

Having fully described my invention, what I claim as new, and desire to secure by Letters Patent, is—

1. In a striking-train for clocks, the combination, with the spring-actuated hammer-axle, the hammer, the escapement-disk and the disengaging-arm secured thereon, and the escapement-wheel actuated by a spring or weight, of a notched or grooved disk secured 60 on the center arbor and adapted to engage the disengaging-arm, and the step-faced wheel secured on the hour-hand sleeve and adapted to regulate the stop-lever, substantially as set forth. 65

2. In a striking-train for clocks, a single-toothed escapement-disk secured on a spring-actuated hammer-axle, and adapted to be operated by a spring or weight actuated escapement-wheel, and to be held in check by an 70 arm secured on the hammer-axle, in connection with a disk on the center arbor, substantially as set forth.

3. In a striking-train for clocks, the combination, with an actuated and hammer-actuating escapement-wheel provided with less than twelve stops, of a step-faced wheel adapted to make one revolution every twelve hours, and a two-armed stop-lever adapted to be actuated by the wheel and to stop the escapement-wheel at the proper intervals to strike the twelve hours, substantially as set forth. 75

4. In a striking-train for clocks, the combination, with the movement mechanism, consisting, essentially, of the spring-actuated hammer-axle, the balanced hammer, the escapement-disk, and the disengaging-arm, of the regulating and actuating mechanism, consisting, essentially, of the power-actuated escapement-wheel with its stops, the disk for locking and releasing the disengaging-arm, the wheel, and the two-armed lever, arranged substantially as set forth. 80

In testimony whereof I have signed this specification in the presence of two subscribing 95 witnesses.

ANDREAS GULBRANDSEN HOVDE.
